US00D971706S

(12) **United States Design Patent** (10) Patent No.: **US D971,706 S**
(45) Date of Patent: ** Dec. 6, 2022

(54) **ROTARY IMPACT WRENCH**

(71) Applicant: **MILWAUKEE ELECTRIC TOOL CORPORATION**, Brookfield, WI (US)

(72) Inventors: **Jacob P. Schneider**, Cedarburg, WI (US); **Joseph H. Ellice**, Greenfield, WI (US); **Sara Burch**, Milwaukee, WI (US); **Evan Brown**, Milwaukee, WI (US); **Andrew J. Weber**, Cudahy, WI (US); **Scott R. Fischer**, Menomonee Falls, WI (US)

(73) Assignee: **MILWAUKEE ELECTRIC TOOL CORPORATION**, Brookfield, WI (US)

(**) Term: **15 Years**

(21) Appl. No.: **29/814,483**

(22) Filed: **Nov. 5, 2021**

(57) **CLAIM**

We claim the ornamental design for a rotary impact wrench, as shown and described.

DESCRIPTION

FIG. 1 is a front perspective view of a rotary impact wrench embodying our new design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The broken lines in the drawings illustrate portions of the rotary impact wrench that form no part of the claimed design.
